UNITED STATES PATENT OFFICE.

JAMES SHARKEY, OF BROOKLYN, NEW YORK.

DESIGN FOR MONUMENTS.

Specification forming part of Design No. 7,416, dated May 5, 1874; application filed March 21, 1874.
[Term of Patent 7 years.]

To all whom it may concern:

Be it known that I, JAMES SHARKEY, of Brooklyn, Kings county, and State of New York, have invented a Design for Obelisks, of which the following is a specification:

The nature of my design is fully represented in the accompanying photographic illustration, to which reference is made.

A is the base. B is the pedestal, which has four tablets, C, on the four curved sides D. E is an arch above each of the tablets, the base ends of which arches rest on ornamental trusses F. The base ends of the arches are coiled up in the shape of scrolls G. H is an ornamented extension of the pedestal. I is

the shaft, which is square in cross-section to correspond with the pedestal and base. The arches E form the novel and essential feature of the design.

Having thus described my invention, I claim—

The design for an obelisk, in which the tablets are surmounted by arches E, resting on ornamented trusses F, substantially as shown and described.

JAMES SHARKEY.
